[57] **CLAIM**

The ornamental design for an adjustable support stand for an electronic device, substantially as shown and described.

DESCRIPTION

FIG. 1 is a perspective view of our design for an adjustable support stand.

FIG. 2 is a top plan view thereof.

FIG. 3 is a front elevational view thereof.

FIG. 4 is a side elevational view of the stand wherein the same is disclosed in an alternate position.

FIG. 5 is a bottom plan view thereof.

The dotted line representation of a stereo tuner in FIGS. 3 and 4 is for illustrative purposes only.

FIG. 1

FIG. 2

FIG. 4
